UNITED STATES PATENT OFFICE.

JOHN BORGE, OF NEW YORK, N. Y., ASSIGNOR TO BORGE INCINERATOR CORPORATION, OF NEW YORK, N. Y., A CORPORATION OF NEW YORK.

INCINERATOR.

1,275,652.

Specification of Letters Patent. Patented Aug. 13, 1918.

Application filed April 6, 1916, Serial No. 89,300. Renewed January 11, 1918. Serial No. 211,455.

To all whom it may concern:

Be it known that I, JOHN BORGE, a subject of the King of Norway, and a resident of the city of New York, county of Kings, 5 and State of New York, (whose post-office address is Flatiron Building, New York city,) have invented a new and useful Improvement in Incinerators, of which the following is a specification.

10 The object of my invention is to provide a simple, economical and durable incinerator which may be operated with gaseous or liquid fuel for the purpose of incinerating garbage and other material at a minimum 15 expense and without objectionable gases or other resulting products. This object is accomplished by my invention, one embodiment of which is hereinafter more particularly set forth in the accompanying drawings, in which—

Figure 1 is a sectional perspective view showing a portion of my improved incinerator with its sheathing omitted;

Figs. 2 and 3 are sectional views, taken 25 on the lines 2—2 and 3—3 respectively, of Fig. 4, looking in the direction of the arrows;

Fig. 4 is a longitudinal central section of my improved incinerator;

30 Figs. 5 and 6 are sectional views, taken on the lines 5—5 and 6—6 respectively, of Fig. 4, looking in the direction of the arrows.

Throughout the various views of the 35 drawings, similar reference characters designate similar parts.

My improved incinerator 1 is provided with a garbage or other refuse receiving chute 2 placed near its upper front and 40 closed by a hinged cover 3, a flue 4 placed at the upper rear portion of its top, a series of burners 5 connected to a main 6, and an ash pit door 7 below the burners 5 and mounted in the conventional manner. The 45 burners 5 are opposite openings 8 in the front 9 of the incinerator so that flames may be blown through its front against the garbage in a manner which will be described below. The front 9 is preferably made of 50 cast iron, and in the rear of the same is an asbestos or other heat insulating sheath which is placed wherever convenient on all sides and the top of the incinerator so as to make the device as efficient as possible. The 55 sides of my improved incinerator and the

top have the asbestos sheathing 10 covered by wrought or cast iron protecting sheets 11, which may be made in any suitable way.

It is apparent from Fig. 1 that the greater part of my improved incinerator is composed of refractory or other similar fire resisting material of some strength and substance with the parts arranged as shown; that is, the top tile 12 has the flue 4, as above described, at its rear, and below its front there is a garbage receiving opening 13 placed in the downwardly extending upper front-tile 14. The walls of the opening 13 are extended so as to cover the front flue, in a manner which will be described below. 70

The top 12 is supported at the rear by the vertically disposed slabs 15 and 16, the former being the lower, and these slabs are connected by a tongue and groove joint or any other suitable means. The sides 17 and 18 are made of a number of slabs in a similar manner and also support the top tile 12, and the front 19 is also made with slabs with openings 8, as above described, and also an opening 20 for the ash pit opposite 80 the door 7.

An interior set of tiles 21 and 22 run parallel to the tiles 15 and 16, except where the tile 22 is warped at its upper edge so as to conform to the flue 4, as shown. These 85 tiles are so placed as to form a flue between them and the outer tiles 15 and 16, and gases can pass into this flue through a recess 23 at the bottom, and through perforations 24 and 25 at higher levels. At the front another tile 90 26 is placed which runs parallel with the tiles 21 and 22 and extends from the ash pit to a point below the upper front tile 14 and it is recessed at 26^a so as to leave ample space for gases and vapors to flow both above 95 and below, and it is slotted, as shown at 27, so as to permit the flames from the burners 5 to enter the garbage receiving chamber and also to permit volatile products from the garbage to reach the flames and be burnt. 100

The bottom of the garbage receiving chamber is closed by a suitable dumping grate 28 which may be of any suitable form, and normally lies horizontal.

In view of the foregoing, the operation of 105 my improved incinerator will be readily understood. From time to time, the cover is raised and garbage is deposited in the chute 2 and at once finds its way to the garbage chamber between the tiles 21 and 22 on the 110

- one hand the tile 26 on the other and above the grate 28 and below the top tile 12. Here the garbage is allowed to accumulate until a large enough amount is present to justify 5 its incineration, which occurs when the burners 5 are lighted in the usual manner so that flames pass from them through the openings 8 and slots 27 against the garbage and also over the top of the garbage through the recess 10 26^a; and the light products of combustion, through the holes 24 and 25. As the garbage is heated, its volatile products mix with the products of combustion, the heavier passing out through the slots 27 and through the 15 openings in the grate 28 to the ash pit where they are drawn up the rear flue to the flue 4 and the lighter products pass through the openings 24 and 25 and thence up the rear flue.
- 20 When in use, the rear flue soon becomes intensely hot and then becomes a combustion chamber.
- When the volatile products have been driven off and nothing remains except the 25 ashes, the ashes may be dumped into the ash pit and allowed to accumulate and finally removed from time to time. If the ash pit gets too full these ashes may be deposited in the chute 2, along with more garbage, and 30 this may be repeated for several times before it is necessary to remove the ashes.
- While I have shown and described one embodiment of my invention, it is obvious that it is not restricted thereto, but is broad

enough to cover all structures that come 35 within the scope of the annexed claim.

Having thus described my invention, what I claim is:—

In a device of the class described, a chamber having a top, a bottom, a pair of side 40 walls, a front wall and a rear wall, a pair of vertical partitions extending from side wall to side wall within the chamber forming a garbage receiving chamber between them and also forming flues between them and 45 the front and rear walls respectively, the front wall having an opening leading to the garbage chamber, the front partition having its upper end terminating below said garbage receiving opening and having its lower 50 end terminating above the bottom of the furnace, a garbage supporting grating extending between the partitions, the front partition being provided with a grated portion, the front wall having openings directed toward 55 the grated portion in the front partition, burners adapted to force flames through the openings in the front wall and through the grated portion of the front partition, the rear partition having a plurality of openings 60 above the garbage supporting grate and having an opening below said grate leading to the rear flue and the top of the chamber having an outlet opening leading from said rear flue.

Signed at the city, county and State of New York, this 29th day of March, 1916.

JOHN BORGE.
